UNITED STATES PATENT OFFICE.

WILLIAM WINT MORGAN, OF PHILADELPHIA, PENNSYLVANIA.

DESIGN FOR A PLUMBER'S BIB.

Application filed October 18, 1923. Serial No. 7,530. Term of patent 3½ years.

To all whom it may concern:

Be it known that I, WILLIAM WINT MORGAN, a citizen of the United States, residing at Philadelphia, in the county of Philadelphia and State of Pennsylvania, have invented a new, original, and ornamental Design for a Plumber's Bib, of which the following is the specification, reference being had to the accompanying drawing, forming part thereof.

I claim:—
The ornamental design for a plumber's bib as shown.

WILLIAM WINT MORGAN.
